O. A. OLSON,

LETTERING INSTRUMENT,

APPLICATION FILED SEPT. 7, 1921.

1,416,411.

Patented May 16, 1922.

INVENTOR
Oscar A Olson

By Drury & Hague Atys.

UNITED STATES PATENT OFFICE.

OSCAR A. OLSON, OF AMES, IOWA.

LETTERING INSTRUMENT.

1,416,411.

Specification of Letters Patent. Patented May 16, 1922.

Application filed September 7, 1921. Serial No. 499,985.

To all whom it may concern:

Be it known that I, OSCAR A. OLSON, a citizen of the United States, and resident of Ames, in the county of Story and State of Iowa, have invented a certain new and useful Lettering Instrument, of which the following is a specification.

The object of my invention is to provide a device of simple, durable and inexpensive construction, which may be used by draftsmen to draw parallel guide lines for lettering.

More specifically it is the object of my invention to provide in a device having a series of rows of symmetrically arranged openings to be used in drawing parallel lines, improved means for mounting the said device.

My invention consists in the construction, arrangement and combination of the various parts of the device, whereby the objects contemplated are attained, as herein-after more fully set forth, pointed out in my claims, and illustrated in the accompanying drawings, in which:

Figure 1 is a front elevation of my improved device.

Figure 2 is a front elevation of same, showing it tilted to one of its positions for drawing diagonal lines.

Figure 3 is a sectional view, taken on the line 3—3 of Figure 1; and

Figure 4 is an end elevation of Figure 1.

My improved device comprises a disc 10, which is preferably formed of transparent material such as celluloid, having its peripheral edge provided with an annular groove 11. This member 10 is rotatably mounted in a frame 12, which is preferably formed of a single piece of wire. This frame comprises a straight portion 13, which is of a length considerably greater than the diameter of the disc 10, and is provided with loop portions 14 and 15 at its ends, the said loops being in the same plane and in the same direction. The loop 14 is provided with an inwardly extended portion 16, and the loop 15 is provided with an inwardly extending portion 17. The portion 16 is of a greater length than the portion 17. The portion 16 is provided with a curved portion 18, which has an outwardly extending curved portion 19 at its ends. The member 17 is provided with a curved portion 20 having an outwardly curved portion 21 at its outer end.

The curved portions 18 and 20 are arched on substantially the same circle as the disc 10. The members 18 and 20 are of the same curvature as the disc 10, and designed to enter the groove 11, and are so arranged that when the said disc 10 is placed between them, the said members 18 and 20 will have to be sprung apart a slight distance so that the said members will enter and frictionally engage the groove 11, the said members also being so arranged that one portion of the groove 11 will engage the inner face of the member 13.

By this arrangement it will be seen that the disc 10 is rotatably mounted in the members 13, 18 and 20, and frictionally held against rotary movement by the resiliency of the loop members 14 and 15. The member 16, as before stated, is longer than the member 17, and the ends 19 and 20 are so arranged that the instrument may be tilted, as shown in Figure 2, with the members 15 and 21 adjacent to a suitable straight edge, and when so tilted the member 13 will produce an angle of substantially 75 degrees with the straight edge, and the member 13 used as a straight edge for drawing inclined lines at an angle of 75 degrees with the base line.

By tilting the instrument to another position, with the loop 14 and the end 19 adjacent to the straight edge, the member 13 will then assume an inclined position in the opposite direction from that shown in Figure 2, and at an angle of substantially 68 degrees with the base line, instead of 75 degrees. These two angles are the standard angles for the vertical guide lines of standard lettering.

For drawing the horizontal lines I have provided a series of openings 22 in the member 10, and I have arranged these openings in rows, one of the rows being in a diametrical line through the said member 10, and provided with a series of equally spaced openings 23.

These openings 23 are made tapering, as shown in section in Figure 3, so that as the member 10 is held flat on the paper, a lead pencil point may be inserted through said opening, and when the member 13 is placed adjacent to a straight edge the pencil may be moved in a parallel relation with said straight edge, and a parallel line drawn parallel to said straight edge. When it is desired to draw another line parallel with

the first line, the pencil point is placed in another one of the openings, and a like line may be drawn in the same manner and parallel thereto.

5 Thus it will be seen that by placing the pencil point in any one of the openings 23, lines may be drawn parallel with the straight edge, and an equal distance apart.

10 For lettering it is usually desirable to draw the lines in groups of three, the upper and lower lines of the group being spaced apart a distance equal to the total heights of the capital letters, and the intermediate line drawn closer to the top line than to the bottom line, so that the distance between the said intermediate line and the bottom line represents the height of the small letters. To accomplish this with the instrument, I preferably provide a row of 15 openings on each side of the row of openings 23, and parallel therewith, each of these rows of openings being provided with groups of openings spaced the same as the lines above described, and one of the rows 20 of openings being provided with a different spacing than the other.

The instrument may then be used in the same manner as when drawing parallel lines, and when set as shown in Figure 1, 30 with the central row of openings 23 perpendicular with the member 13, lines of a maximum width may be drawn. When it is desired to draw lines closer together than the openings in the instrument, all that is necessary to do is rotate the said instrument 35 within the members 18 and 20 to the desired amount, and the lines may then be drawn as before described.

In order to readily ascertain the height of 40 the capital letters, I provide a series of graduations 24, extending substantially a quarter of the way around the edge of the member 10. A line 25 is provided on the member 13, and is so arranged that when the instrument is set in the position shown in 45 Figure 1, the total height of the capitals will represent 10/32 of an inch or 5/16 of an inch. When the disc is rotated until the numeral 9 is even with the line 25, the height of 50 the capital letters, or the space between the two extreme lines of each group of three will be 9/32 of an inch, and when the disc is rotated until the numeral 8 is opposite the line 25, the height of the capitals will 55 be 8/32 of an inch or 1/4 of an inch.

The character "3/5" is provided at the top of the column of openings at the left of

the openings 23, which indicates that the height of the space between the intermediate and the lower extreme line drawn by 60 said openings is 3/5 of the total distance between the upper and lower lines for any setting of the disc; and the character "2/3" at the top of the column to the right indicates that the ratio between the intermediate and 65 the lower extreme line drawn by said openings is 2/3 of the total distance between the upper and the lower lines for any setting of the disc.

70 By this arrangement, it will be seen that a large range of spacings of lines may be easily and quickly provided by rotating the member 10, which is always frictionally held in its position by means of the spring members 18 and 20.

75 I claim as my invention:

1. A lettering instrument comprising a frame having a straight side and spaced oppositely arranged resilient members, and a disc rotatably mounted between said resilient members, said disc being provided with a series of symmetrically arranged openings.

2. A lettering instrument comprising a frame formed of a single piece of wire, having one straight side and two oppositely arranged circular portions, and a disc rotatably mounted between the said circular portions, one side of said disc being designed to engage the said straight portion, said disc 80 being provided with a series of symmetrically arranged openings.

3. A lettering instrument comprising a frame formed of a single piece of wire, having a straight side and a looped portion 95 at each end, each of said looped portions being provided with an inwardly extending portion parallel with said straight portion, one of said inwardly extending portions being longer than the opposite inwardly extending portion, each of said inwardly extending portions being provided with a yielding, oppositely arranged circular portion, a disc having an annular groove in its periphery, the groove being designed to receive the circular portions of said frame, said disc being provided with a diametrical row of equally spaced openings, and a parallel row of groups of openings, each of said groups being provided with openings 100 spaced to represent capital and small letters.

105 Des Moines, Iowa, June 18, 1921.

OSCAR. A. OLSON.
